QUICK-ACTING VISE

Thomas Gorzelany, Mount Clemens, Mich.

Application July 5, 1943, Serial No. 493,612

9 Claims.

(Cl. 81—26)

This invention relates to vises and particularly quick action vises.

An object of the invention is to mount on the base of a vise a unit comprising a sliding jaw and a setting block for such jaw, such unit being quickly movable to a work-clamping position, and to equip said block with mechanism for quickly clamping it to the base and for setting up a high pressure work-clamping reaction between the block and jaw.

Another object is to employ a single actuating element for said mechanism to clamp the block to the base and apply the desired pressure to the jaw.

Another object is to employ cams and preferably cams of an eccentric type to apply high pressures for clamping the block to the base and the sliding jaw to the work.

Another object is to adapt a single actuating element for the block-clamping and jaw-clamping provisions to be adjusted so that, when a quantity of like work pieces are to be successively clamped, the block may be left in a set position, during actuation of said element for clamping and releasing said work pieces.

Another object is to pivot a lever on said setting block and adapt it to actuate one or both of two cams, one of which serves for clamping the block in a set position and the other for applying work-clamping pressure to the sliding jaw.

These and various other objects are attained by the construction hereinafter described and illustrated by the accompanying drawings, wherein:

Fig. 1 is a top plan view of the improved vise, illustrating a work-clamping position thereof.

Fig. 2 is a side elevational view of the same.

Fig. 3 is a cross sectional view on the line 3—3 of Fig. 2.

Fig. 4 is a cross section on the line 4—4 of Fig. 2.

Fig. 5 is a fragmentary longitudinal section, on the line 5—5 of Fig. 4.

Fig. 6 is a fragmentary longitudinal section, on the line 6—6 of Fig. 4.

Fig. 7 is a longitudinal section on the line 7—7 of Fig. 1, showing the handle adjusted to take effect only on the jaw clamping mechanism, and positioned to release clamping pressure.

Fig. 8 is a cross sectional view of the handle on the line 8—8 of Fig. 7.

In these views, the reference character 1 designates an elongated rectangular base having a vise jaw 2 fixed on one of its ends. Said jaw may be held fixed in any desired manner, there

being illustrated two stud bolts 3 headed beneath the base and upwardly extended through the latter to engage the jaw. The bottom face of the base is channeled from end to end thereof, as indicated at 4 to accommodate the heads of said bolts and certain other parts presently to be described. Coacting with the jaw 2 is a sliding jaw 5 having a setting block 6 associated therewith, said sliding jaw and block having depending guide tongues 7 and 7a fitted in a slot 8 which opens upwardly from the channel 4 and extends from the fixed jaw to the opposite end portion of the base. The jaw 5 is slidably held on the base by a clamping piece 9 underlying the base within the channel 4 and having a tongue entering the slot 8 and seating against the tongue of the sliding jaw, said block being clamped to the sliding jaw by a stud bolt 10. The setting block is formed with a central cavity 11 into which project eccentrics 12 and 13 formed terminally on a pair of similar aligned rock shafts 14 journaled in the block transversely to the base and at opposite sides of said cavity. (See Fig. 4.) A shank 15 rigidly projecting from the sliding jaw occupies substantially one half of said cavity and has a thrust block 16 set into a recess thereof to receive the eccentric 12. The other half of said cavity is occupied by a shank 17 upwardly projecting from a clamping piece 18 disposed beneath the base. The clamping piece 18 and adjacent shank have tongues 19 fitted in the slot 8 and meeting therein and are rigidly interconnected by a stud bolt 20. Set into the shank 17 is a thrust block 21 socketed to receive the eccentric 13. The thrust blocks 16 and 21 are afforded a limited sliding transversely to the corresponding shanks but have no material play lengthwise of said shanks. It is preferred, for reasons which will presently appear, to give the eccentric 12 which acts upon the shank 15 an eccentricity approximately twice that of the eccentric 13 acting on the shank 17.

The rock shafts 14 are similarly formed with radial sockets 22 wherein are fitted pins 23 terminally formed on spaced furcations 24 and 25 of a lever for rocking said shafts, the setting block having slots 26 in its ends to allow engagement of the pins in said sockets and allow the desired swinging of the furcations. Said lever comprises a tubular handle 27 receiving a long shank 28 on one of the furcations and a short shank 29 on the other, said handle being rotative on said shanks. A pin 30 transversely set into the shank 28 projects oppositely from said shank to engage in a pair of spiral slots 31 oppositely formed in

the tubular handle. (See Fig. 7.) This has the effect of retracting the handle when same is rotated, the slots being of sufficient length to permit of such retraction as will disengage the handle from the short shank. To positively retain the pins 23 in the sockets 22, screws 32 are centrally set into the outer ends of the two rock shafts and engage recesses in said pins. Preferably the tubular handle of the lever has a suitable grip 33 telescoped thereon, formed of fiber or the like.

In use of the described vise, the lever is adapted to actuate both rock shafts 14 when the handle 27 is in its forward position, embracing the shanks of both furcations 24 and 25. This adjustment of the handle is preferred when differently dimensioned work pieces are to be clamped, it being consequently necessary to shift the unit comprised by the setting block and sliding jaw preliminary to successive insertions of said pieces. When a quantity of like work pieces are to be successively vised, the operator sets the sliding unit in position, lowers the lever to clamp the setting block 6 to the base and to clamp the initial work piece between the jaws, and then rotates the handle to effect its retraction and release the shank 29. Thereafter the lever is effective on only one of the rock shafts, namely that carrying the eccentric 12, which takes effect through the shank 15 on the sliding jaw. While movement of said jaw relative to the setting block is slight and preferably less than one sixteenth of an inch, it is ample to afford insertion and removal of work pieces.

In clamping the setting block to the base, it is to be understood that the eccentric 13 is raised slightly as it shifts about the axis of the corresponding rotating rock shaft, and this imposes a powerful upthrust on the shank 17 and hence on the clamping piece 18. Said shank and thrust piece respond only to the vertical component of the force applied by said eccentric since horizontal play of the thrust block 21 neutralizes the horizontal component of said force.

In applying clamping pressure to the jaw 5, the eccentric 12 moves slightly toward the fixed jaw 2 as said eccentric shifts about the axis of the corresponding rotating rock shaft, imposing a powerful thrust on the shank 15 and hence on the sliding jaw which carries said shank. Said shank and jaw respond only to the horizontal component of the force applied by the eccentric, since vertical play of the thrust block 16 neutralizes the corresponding component of said force.

There are two reasons for a greater eccentricity of the eccentric 12 than that of the eccentric 13. First, such clamping travel of the sliding jaw as will afford ready insertion of work in the vise must materially exceed the lifting effect which must be imposed on the shank 17 to clamp the setting block in place. Second, when the two eccentrics are actuated in common, it is necessary that the clamping pressure applied to the jaw 5 continue to increase somewhat after the clamping effect on the setting block has reached a substantial maximum. It is to be understood that concurrent actuation of the two eccentrics entails some slight sliding retraction of the setting block as the eccentric-induced forces build up, the block thus accommodating itself to the reaction of eccentric 12, after the jaw 5 is restrained by the work from further response to said eccentric.

The described vise is suited to save time in any

operation entailing the vising of work, and is particularly economical of both time and labor when a quantity of like articles are to be successively vised.

5 It will be understood that the base of the vise may be fastened down, if desired to a work table or other support but in most uses the vise may rest freely on a supporting surface.

What I claim is:

10 1. A vise comprising a base, a clamping jaw fixed on the base, a unit slidable on the base to and from said jaw, such unit including a jaw paired with the fixed jaw and a setting block, mechanism carried by the setting block for clamping it to the base, mechanism carried by the setting block for applying work-clamping pressure to the sliding jaw, and a lever means mounted on the setting block and operatively engageable with both said mechanisms to actuate them in common and alternatively disengageable from the mechanism for clamping the setting block to the base, whereby said lever means may solely actuate the mechanism for applying pressure to the sliding jaw.

15 25 2. A vise comprising a base, a clamping jaw fixed on the base, a unit slidable on the base to and from said jaw, such unit including a jaw paired with the fixed jaw and a setting block, a pair of aligned rock shafts journaled in the setting block, a lever adapted to rock both said shafts, means for clamping the setting block to the base responsive to one of said shafts, the lever being adjustable to release it from the last-mentioned shaft, while maintaining its operative connection to the other shaft, and means for applying work-clamping pressure to the sliding jaw from the other of said shafts.

30 35 3. A vise comprising a base, a clamping jaw fixed on the base, a unit slidable on the base to and from said jaw, such unit including a jaw paired with the fixed jaw and a setting block, a clamping piece for the setting block adapted to seat upwardly on the base, an element rotative on the setting block for applying a clamping reaction to the setting block and said clamping piece, an element rotative on the setting block for imposing work-clamping pressure on the sliding jaw, and a lever comprising a handle and furcations respectively effective on the respective 40 45 50 55 said elements, the furcations having shanks differing in length and said handle embracing said shanks, and a pin transversely carried by the longer shank and engaging a substantially spiral slot in the handle, whereby the handle may be retracted by rotation on said shanks, to disengage it from the shorter shank.

60 65 70 4. A vise comprising a base, a clamping jaw fixed on the base, a unit slidable on the base to and from said jaw, such unit including a setting block and a jaw paired with the fixed jaw, a clamping piece for the setting block seating upwardly against the base, a shank attached to the clamping piece and extending upwardly into the setting block, a shank attached to and extending rearwardly from the sliding jaw into the setting block, a cam rotatively mounted in the setting block and reacting on the upwardly extending shank to clamp the setting block on the base, a cam rotatively mounted in the setting block and reacting on said rearwardly extending shank to apply work-clamping pressure to the sliding jaw, and means for rotating said cams.

5. In a vise as set forth in claim 4, two substantially aligned rock-shafts journaled in the setting block and respectively carrying the re-

spective cams, said shanks extending between the rock-shafts for actuation by the cams.

6. A vise comprising a base, a clamping jaw fixed on the base, a unit slideable on the base to and from said jaw, such unit including a setting block and jaw paired with the fixed jaw, a cam rotatively carried by the setting block and effective to clamp such block to the base, a cam rotatively carried by the setting block and effective on the sliding jaw to impose work-clamping pressure on such jaw, a lever taking effect on both said cams to rotate the cams, and an element adjustable on the lever to effect its release from one of said cams.

7. A vise as set forth in claim 6, the last-mentioned element being a handle adjustable longitudinally on the lever to effect its release from one of the cams.

8. In a vise, a unit comprising a setting block, a jaw movable relative to said block for work-clamping purposes, two substantially aligned rock-shafts journaled in the setting block, a cam carried by one of said shafts for clamping the

block in a fixed position, a cam carried by the other of said shafts for applying work-clamping pressure to said jaw, said shafts having substantially radial sockets for receiving actuating elements, and the block being recessed from its outer face to said shafts to afford engagement of such elements with the shaft and an effective rocking of such elements.

10 5 9. A vise comprising a base, a clamping jaw fixed on the base, a unit slideable on the base to and from said jaw including a jaw paired with the fixed jaw and a setting block, a pair of aligned rock shafts journaled in the setting block, means for clamping the setting block to the base responsive to one of said shafts, means for applying work clamping pressure to the sliding jaw from the other of said shafts, and a lever having a handle and furcations through which the handle may take effect on the paired rock shafts, the handle being slideable to disengage it from one of said furcations.

THOMAS GORZELANY.
